UNITED STATES PATENT OFFICE.

JOHN B. DRAHONOVSKY, OF MILWAUKEE, WISCONSIN, ASSIGNOR, BY DIRECT AND MESNE ASSIGNMENTS, TO MECHANICAL PRODUCTION CO., OF MILWAUKEE, WISCONSIN, A CORPORATION OF WISCONSIN.

TIMER FOR INTERNAL-COMBUSTION ENGINES.

1,413,011.

Specification of Letters Patent. Patented Apr. 18, 1922.

Application filed May 24, 1919. Serial No. 299,468.

To all whom it may concern:

Be it known that I, JOHN B. DRAHONOVSKY, a citizen of the United States, and resident of Milwaukee, in the county of Milwaukee and State of Wisconsin, have invented new and useful Improvements in Timers for Internal-Combustion Engines, of which the following is a description, reference being had to the accompanying drawings, which are a part of this specification.

My invention relates to certain new and useful improvements in timers for internal combustion engines of that type having a series of fixed contact members spaced apart in a ring or casing of insulating material, and having a revoluble contact member selectively engaging the fixed contact members.

The insulating material now used in devices of this character is of a fibre composition, and has proved very dissatisfactory in that the fibre, being relatively soft, wears down, and also becomes pitted with any foreign matter that may contact therewith. Casings of this character have also proven impracticable in that a film of copper or the like worn from the contact members generally forms thereon, causing a short circuit as will be readily understood by those skilled in the art.

Hence my invention has for its primary object to provide an inner casing or fixed contact carrying ring for timers, which will be made of glass, porcelain, lignum vitae, Russian hickory, or any like hard non-conductor.

Another object of the present invention is to provide a timer having an outer casing and an inner casing readily detachably secured therein and provided with novel means for insulating the fixed contacts from the outer casing.

With the above and other objects in view which will appear as the description proceeds, my invention resides in the novel construction, combination and arrangement of parts substantially as hereinafter described, and more particularly defined by the appended claims, it being understood that such changes in the precise embodiment of the herein disclosed invention may

be made as come within the scope of the claims.

In the accompanying drawing I have illustrated one complete example of the physical embodiment of my invention constructed according to the best mode I have so far devised for the practical application of the principles thereof, and in which:

Fig. 1 is a bottom view, part in plan and part in section of my timer or commutator;

Fig. 2 is a view thereof, part in vertical section and part in side elevation;

Fig. 3 is a detailed view of the inner casing or contact carrying ring detached from the outer casing, and with the contact members removed therefrom.

Referring now more particularly to the accompanying drawing, the numeral 5 designates a support which may form part of the timer, or may be part of the engine casing. As shown, the support is provided with an annular flange 6 providing a recess to receive the inner edge of the timer 75 outer casing 7. The body portion 8 of the casing is of annular form and is closed at its outer side by a conical end portion 9, having an axial recess 10 for receiving the rounded end portion 11 of the member 12 80 which yieldingly holds the casing in the annular recess of the support. The body portion 8 has formed therein a plurality of slots 13 for the purpose hereinafter described.

The casing 7 also has its portion 8 split as at 14, and provided with a pair of opposed ears 15, provided with central apertures for receiving an adjoining bolt 16, this construction readily detachably securing in the portion 8 an inner casing or contact carrying ring 17. The ring 17 has formed on its outer periphery a plurality of spaced laterally projecting hubs or lugs 18 for engagement in the slots 13 of the 95 casing, and in each lug 18 is a central aperture to receive the shank 19, of a contact member 20, seated in a recess 21, formed in the inner periphery of ring 17 at the termination of the bore of each lug 18.

The shanks 19 of the contacts which extended outwardly of lugs 18, are threaded as at 22 to receive a nut 23 for securing the contacts in ring 17, a knurled nut 24 also

engaging the threaded portion 22 to secure the terminals of the various electrical wires leading to the spark plugs, (not shown) of the engine with which the device is being used.

The contact members 20 are engaged by a roller contact 25 which is carried by a roller arm 26 pivotally secured as at 27 to a collar 28 formed on a shaft 29 in gear connection 10 with the cam or crank shaft, (not shown) of the engine with which it is being used. As usual, the shaft 29 is revoluble at one-half crank shaft speed and the roller 25 selectively engages the contacts 20 to distribute 15 the electrical energy to the spark plugs, (not shown) of the various engine cylinders in their proper order. The roller 25 is held in resilient engagement with the inner periphery of 17 by means of a 20 spring 30.

In order to conveniently lubricate the working parts of the timer, an oil hole 31 is provided in the portion 9 of the casing and is normally covered by means of a 25 spring controlled cap 32. The slit 14 of the casing is positioned at the bottom so that all excess oil will drain therefrom. The casing 7 is further provided with a radially extending arm 33 to form a handle for adjusting 30 the casing to advance or retard the spark with relation to the engine of which the timer forms a part.

The inner casing or ring 17 is composed of glass, porcelain, Russian hickory, lignum 35 vitæ, or any other desired insulating material of the proper hardness, so that the roller 25 in tracking over the same will not deposit a thin film of material from contacts 20 and thus will prevent the passage of 40 electrical energy from one contact 20 to the other. When the rings 17 are made of fibre, a film of copper deposit is formed on the inner periphery thereof after the same has been used for a short while, and considerable 45 trouble is had in that the current will travel from one contact 20 to the other, and thus cause the engine with which it is being used to miss. Further, any foreign matter which may be deposited on the inner surface of

ring 17 is worked in the fibre by means of 50 roller 25, but in my device this is impossible as will be readily understood.

From the foregoing description, it will be seen that my timer is a very simple construction, that the inner casing or contact carrying ring is readily detachable from the outer casing, that the inner casing is of hard wearing substance, and that the timer is well adapted for the purpose as described.

What I claim as my invention is:

1. A timer, comprising, an outer casing having one end open, said casing being slotted adjacent its open end, an inner casing, a laterally projecting lug formed on the periphery thereof and engageable in the slot 55 of the outer casing, a contact surface in the inner casing and having a terminal passed through said laterally projecting lug, and a revoluble contact member adapted to engage said first named contact member.

2. A timer, comprising, an outer casing provided with an annular base portion having formed therein a plurality of spaced slots, a contact carrying ring engageable in said casing, a plurality of spaced laterally 75 projecting lugs on said ring and engageable with the slots of said casing, and means for detachably securing said ring in said casing.

3. A timer, comprising, an outer casing provided with an annular base portion having a plurality of slots spaced substantially 80 90 degrees apart, a ring member provided with a plurality of radially extending lugs spaced substantially 90 degrees apart and engageable with the slots of the casing, said 85 lugs being centrally bored and said ring having formed in its inner peripheral surface a plurality of recesses adjacent the bores of said lugs, contact members in said recesses and provided with shanks engaging the bores of said lugs and extended outwardly thereof, and a revoluble contact arm adapted to track on the inner peripheral surface of said ring to selectively engage said 90 contact members.

In testimony whereof, I affix my signature.

JOHN B. DRAJIONOVSKY.
